(57) **CLAIM**

The ornamental design for an elongated umbrella hitch mount assembly for a vehicle, substantially as shown and described.

DESCRIPTION

FIG. 1 is a left side elevation view, partly in perspective, of an elongated umbrella hitch mount assembly for a vehicle showing my new design, the sport utility vehicle in dashed lines not forming a part of the design;

FIG. 2 is a rear elevation view thereof, partly in perspective, the sport utility vehicle in dashed lines and the dashed-line elements of the umbrella not forming a part of the design; FIG. 3 is another rear elevational view thereof, partly in perspective, showing a variation of my design in which the umbrella is rotated to a transverse orientation, the sport utility vehicle in dashed lines not forming a part of the design;

FIG. 4 is a right side elevation view thereof, partly in perspective, the pickup truck in dashed lines not forming a part of the design;

FIG. 5 is a front elevation view thereof, partly in perspective, the umbrella elements in dashed lines not forming a part of the design;

FIG. 6 is a bottom perspective view thereof, looking upward at my design, the umbrella elements in dashed lines not forming a part of the design; and,

FIG. 7 is a top plan view thereof.
